UNITED STATES PATENT OFFICE.

LEWIS PIRDUN, OF TULSA, OKLAHOMA.

BURNER

1,171,137.

Specification of Letters Patent.

Patented Feb. 8, 1916.

Application filed April 16, 1915. Serial No. 21,716.

To all whom it may concern:

Be it known that I, LEWIS PIRDUN, a citizen of the United States, and a resident of Tulsa, in the county of Tulsa and State of Oklahoma, have invented certain new and useful Improvements in Burners; and I do hereby declare the following to be a full, clear, and exact description of the invention, such as will enable others skilled in the art to which it appertains to make and use the same.

This invention relates to improvements in burners and more particularly to such as may be employed for supplying fuel to furnaces in which fluid fuel is employed.

One object of the invention is to so construct the burner that it may be operated to supply either gaseous or liquid fuel with steam or air, or so that both gaseous and liquid fuel may be mixed and injected with steam or air or both into the furnace.

A further object is to provide burner appliances of the character specified, whereby the supply of oil and steam may be automatically governed by the steam pressure in the boiler of the furnace with which the burner is employed, or whereby gas supplied to the burner may be similarly governed automatically.

With these and other objects in view, the invention consists in certain novel features of construction and combinations of parts as hereinafter set forth and pointed out in the claims.

In the accompanying drawings; Figure 1 is a top plan view of the device, partly in section; Fig. 2 is a sectional view on the line 2—2 of Fig. 1; Fig. 3 is a sectional view on the line 3—3 of Fig. 1; Fig. 4 is a sectional view on the line 4—4 of Fig. 3, and Figs. 5 and 6 are detail views.

1 represents a cylindrical shell comprising two parts securely bolted together, and from one of said parts of the cylindrical shell, a plate 2 projects. A bonnet or casing 3 is secured to the plate 2 and the cylindrical shell, to form a chamber 4 into which steam is led preferably from the steam dome of the boiler furnace to which my improved burner supplied fuel,—such steam in the chamber 4 being utilized in the operation of the burner as hereinafter explained.

The cylindrical shell 2 is threaded at one end for the reception of a nozzle 5 from which the fuel will be projected, and this

nozzle may be made at its outlet end with a threaded socket 6 to receive a cap 7 for closing the same when not in use. The rear portion of the nozzle 5 is made with a cavity 8 into which the outlet end of an inner nozzle or tube 9 projects,—said nozzle or tube 9 being located within and spaced from the wall of the cylindrical casing 1 and having its outlet end sufficiently spaced from the bore of the nozzle 5 to permit the passage of steam from the shell 1 to said bore of the nozzle 5. The rear end of the inner nozzle 9 projects beyond the rear end of the shell and is threaded exteriorly for the reception of a jam nut 10 and a coupling 11. The coupling 11 carries a manually operable air inlet valve 12, and through said coupling, a gas inlet pipe 13 projects,—said gas pipe projecting past the air inlet valve 12 and terminating forwardly of the same within the rear portion of the inner nozzle or tube 9.

The cylindrical shell 1 is provided interiorly with a beveled annular flange 14 and the tube 9 is provided exteriorly with two annular shoulders 15 and 16. A close fit between the shoulder 15 and flange 14 is effected by suitable packing interposed between them, and a close fit between the shoulder 16 and the rear end of the shell 1 is effected in a similar manner. By the provision of the internal annular flange 14, said shell is divided into two annular chambers 17 and 18, the latter chamber communicating with the bore of the outer or forward nozzle 5 at the forward end of the inner nozzle or tube 9.

An inlet pipe 19 for hydrocarbon oil communicates with the chamber 17, and the inner nozzle or tube 9 is provided (where it passes through the chamber 17) with an oil inlet port 20. A valve 21 is employed to control the passage of oil through the port 20 into the nozzle or tube 9, and the stem 22 of this valve passes through a suitable stuffing box 23 on the shell 1, and passes through the chamber 4 formed by the bonnet 3. A lever 24 is pivotally supported by a post or arm 25 within the chamber 4 and the long arm of this lever is pivotally connected with the valve stem 22. A rod 26 is connected with the short arm of the lever 24 and passes into a chamber 27 on the plate 2,—said rod being secured to a diaphragm 28 located within the chamber 27. A steam pipe 28a communicates with the

chamber 27 and is intended to convey steam from the steam dome of the boiler to said chamber, so that the diaphragm 28 will be subjected to the steam pressure of the boiler at all times. Another chamber 29 is also located on the plate 2 and contains a diaphragm 30. This chamber is also connected with the steam dome of the boiler by means of pipe 28^b so that the diaphragm will be at all times subjected to the steam pressure of the boiler. Drain cocks 31 will preferably be provided for the chambers 27 and 29.

A rod 32 is secured to the diaphragm 30 and passes into the chamber 4, wherein it is connected with the short arm of a lever 33, the latter being pivotally supported by a post or arm 34. To the long arm of the lever 33, the stem 35 of a valve 36 is pivotally connected, said valve serving to control the passage of steam from the chamber 4, through a port 37 to the chamber 18 within the shell 9. Both valve stems 35 and 22 project through an opening in the bonnet 3 and are threaded at their free ends for the reception of nuts 38. Disks or washers 39^a on the valve stems adjacent to the nuts thereon, serve as abutments for springs 40 which encircle said stems,—and the other ends of these springs bear against the bonnet 3. It will be observed that the springs 40 tend to move the valves 36 and 21 away from their seats so as to open the steam and oil ports 37 and 20, and that the pressure 35 of steam against the diaphragms 30 and 28 tends to close said valves.

In the operation of my improved burner, gas will enter the rear end of the inner nozzle or tube 9 and mix with the air entering through the valve 12. The mixed gas and air will flow forwardly through the tube 9 and mix with oil entering at the port 20. The forward portion of the tube 9 will be heated by the steam surrounding it in the chamber 18, and thus the oil in the fluid mixture will be vaporized, and the whole will leave the outer nozzle 5 mixed with steam emitted from the chamber 18, the pressure of such steam also serving to carry 50 the fluid fuel into the first box of the furnace in a manner to insure perfect combustion.

As the supply of oil and steam to be mixed in the burner is governed by the boiler steam pressure automatically operating the valves 21 and 26 as previously explained, the supply of oil and steam will be commensurate with the need to maintain the necessary combustion in the fire box without waste. As the pressure of steam in the boiler increases, the oil valve 21 will operate to restrict the flow of oil into the inner nozzle or tube 9, and the valve 26 will be similarly operated to reduce the flow of steam to the chamber 18 within the shell 1.

If gas is not available the burner may be operated with mixed air, oil and steam, the quantity of oil and steam being automatically controlled so as to provide a mixture which will insure complete combustion, by the operation of the valves 21 and 26. If an adequate supply of gas is available, the oil supply may be cut off and gas may be introduced into the chamber 4, so that its supply to the burner may be regulated and controlled by the operation of the valve 26.

It will be observed that my improved burner is adaptable for use with mixtures of air, gas, oil and steam, or with oil, air and steam, or with air and gas, as the circumstances in any given case may require.

Various slight changes might be made in the details of construction of my invention without departing from the spirit thereof or limiting its scope and hence I do not wish to restrict myself to the precise details herein set forth.

Having fully described my invention what I claim as new and desire to secure by Letters-Patent, is:—

1. In a burner, the combination with an elongated shell having a nozzle outlet at one end, of an inner nozzle passing through said shell and terminating at its forward end near the nozzle outlet of the shell, said inner nozzle and shell forming two annular chambers, means isolating said chambers from each other, an oil inlet communicating with one of said annular chambers, an automatically actuated valve for controlling the passage of oil from said last-mentioned chamber into the inner nozzle, a steam inlet communicating with the forward annular chamber, automatically actuated valve for controlling the passage of steam through said steam inlet, and an air inlet communicating with the inner nozzle in rear of the oil inlet.

2. In a burner, the combination with an elongated shell, and a nozzle at the forward end thereof, of an inner nozzle passing through said shell and terminating near the first-mentioned nozzle, automatically controlled means for admitting steam between the shell and the inner nozzle, separate automatically controlled means for admitting oil into the rear portion of the inner nozzle, and a gas inlet communicating with the inner nozzle in rear of the oil inlet.

3. In a burner, the combination with a nozzle, and a shell inclosing the same, said shell being divided into rear and forward annular chambers, of means for supplying oil to the rear annular chamber, means for controlling the passage of oil from said rear chamber into the nozzle, means for supplying steam to the forward annular chamber, and a forward nozzle communicating with said first-mentioned nozzle and with the annular steam chamber.

4. In a burner, the combination with an elongated shell having an internal annular flange, and a forward nozzle secured to said shell, of an inner nozzle inclosed within said shell and communicating with the forward nozzle, said inner nozzle having an annular shoulder coöoperating with the annular shoulder in the shell, to form two annular chambers within the shell, the forward of said chambers communicating with the forward nozzle, means for controlling a supply of steam to the forward annular chamber, means supplying oil to the rear annular chamber, and means for controlling flow of oil from said rear annular chamber into the inner nozzle.

5. The combination with an elongated burner nozzle and a forward nozzle communicating therewith, of means forming two

annular chambers around said elongated nozzle, the forward of said chambers communicating with the forward nozzle, means for controlling the supply of steam to said forward chamber, means for supplying oil to the rear annular chamber, a valve for controlling the passage of oil from said chamber into the elongated nozzle, a pivoted lever having one arm connected with the stem of said valve, and a steam actuated diaphragm connected with the other arm of said lever.

In testimony whereof, I have signed this specification in the presence of two subscribing witnesses.

LEWIS PIRDUN.
